UNITED STATES PATENT OFFICE.

JOHN A. YARGER, OF NEW HAMPTON, IOWA.

GAME-COUNTER.

SPECIFICATION forming part of Letters Patent No. 394,900, dated December 18, 1888.

Application filed February 25, 1888. Serial No. 265,267. (No model.)

To all whom it may concern:

Be it known that I, JOHN A. YARGER, of New Hampton, in the county of Chickasaw and State of Iowa, have invented a new and 5 useful Improvement in Game-Counters; and I do hereby declare that the following is a full, clear, and exact description of the same.

My invention is an improved register or counter, and in the particular form herein 10 shown and described is adapted for the use of base-ball umpires for registering balls, strikes, and the number of innings played, though it will be obvious that by changing its construction slightly it may be adapted for use as a 15 counter for any game.

The principal object of the invention is to provide such an apparatus that after a certain fixed number of registrations have been 20 made the next attempt at registering will result in sending all of the pointers or hands back to their normal position.

The invention therefore consists, broadly, 25 of a shell or case having a suitable dial-face, containing within it toothed wheels fixed to suitable shafts and acted upon by suitable 30 push and holding pawls and retracting-springs, said shafts carrying pointers or hands for indicating on the dial the desired numbers.

35 The invention further consists in the combination, with the above-mentioned elements, of means for returning the pointers to their normal position automatically upon an attempt to register beyond a certain number.

40 Further, the invention consists in means for returning the pointers to their original positions whenever the operator desires; and, finally, it consists in the various details of construction and arrangement of the parts, 45 whereby I am enabled to attain the end sought to be accomplished.

My invention is shown in the accompanying drawings, in which—

45 Figure 1 is a plan view with the cover and dial in place. Fig. 2 is a similar view with the cover and dial removed. Fig. 3 is a central vertical section of my improved device.

50 In the drawings, the shell or case containing the operating parts is marked A. The cover A' of this case is transparent, in order that the numbers indicated by the pointers may be observed.

Through the center of the face a' of this shell extends the end of a shaft, a, carrying a pointer, b, for indicating the number of balls. 55 The other end of the shaft has its bearings in the back plate.

Near the middle of this shaft, and rigidly secured thereto, is a toothed wheel, B, the teeth thereof being adapted to engage with a 60 spring-pawl, c, pivoted on a post secured to the bottom of the case. This toothed wheel B has rigidly attached to it or cast with it a smaller toothed wheel, C', the teeth of which are adapted to be engaged by the spring-arm 65 d, secured to the side of the case, said arm having a projection extending through a slot to the outside of the case, and having a button attached to the end of said projection, whereby upon pushing upon the said button 70 the shaft a will be rotated, and thus the pointer b caused to register.

Attached at one end to the under side of the wheel B, and at the other end to the bottom of the case, is a coil-spring, e, adapted to be 75 placed under tension by the rotation of the shaft when the pointer b is registering, and adapted when the wheel B is forced out of engagement with the pawl c to return it to its normal position, which in the present case 80 will happen just as the pointer b reaches the number 5 on the dial.

In order to accomplish this return of the shaft to its normal position automatically when the desired number is reached, I form 85 upon the under side of the wheel B a projection, f, extending out beyond the periphery of said wheel, and this projection is so placed upon the wheel that after the pointer passes the fourth number the projection f will ride 90 up upon an inclined plane, f', secured in proper position on the bottom of the case, which will thus force the wheel up out of engagement with the pawl c, when the spring e will act to return the mechanism to its normal position above the pawl, a recess being 95 formed in the place of one of the teeth for the pawl to come into line with the wheel again, which it will do under the action of its spring, and thus be ready for a continuation of its 100 action.

The mechanism for indicating the number of strikes which a batter has had is as follows: Loosely carried upon the upper part of

the shaft *a* is a sleeve, *D*, carrying on its upper end the pointer *b'*, and having rigidly secured to it a toothed wheel, *E*, similar to the wheel *B*, engaging with the pawl *h*, having cast with it a toothed wheel, *F*, similar to the wheel *C'* before described, and an arm, *d'*, operates the pointer in the same manner as the arm *d* does the other mechanism. This wheel *E* has a projection, *g*, adapted to ride up upon an inclined plane, *g'*, between the second and third spaces, and thus force the wheel *E* out of engagement with the pawl *h*, the mechanism being returned to its proper position by means of the spring *k*, shown as attached one end to the wheel *E* and the other end to the side of the case, and adapted to be put under tension by the rotation of the sleeve *D*. It will thus be seen that both wheels, one carried by the shaft and one by the sleeve, are operated by push-pawls, and are released from these pawls by elevating the wheel through inclines upon the plane of the pawls. The springs heretofore described serve to retract them for a fresh start. In order to return these wheels to the plane from which they started, I have provided a spiral spring upon the sleeve, (indicated at *R*.) which exerts constant pressure upon the wheel, and when said wheels have been returned to their normal position the spiral spring forces them down to the plane of their respective pawls. As heretofore described, at a point upon each wheel a space is cut out between two teeth, which allows the wheel when returned by its retracting-spring to be forced down in line with its pawl, the recess permitting of this movement, as it extends beyond the inwardly-projecting end of the said pawl, and in the first movement of each wheel the pawl immediately comes in contact and works over a tooth.

In order to indicate the number of innings, I have supported a ratchet-wheel, *m*, beneath the cross-standard, which carries upon a pin 45 tle an index-finger which registers the number of innings played on the dial-face, a graduated circle being arranged to one side of the center, as shown. This ratchet-wheel may have its teeth so formed as to require two 50 movements of the push-pawl *M* (the thumb-piece of which extends outside of the shell) to indicate a single inning, the single movement indicated carrying the pointer, for instance, between 8 and 9, showing that eight 55 and one-half innings have been played. A suitable spring, 10, as shown, keeps the ratchet-wheel from movement, except when operated upon by the push-pawls.

In case it is desired to return the parts to 60 their normal position after a certain number of balls or strikes, both wheels can be thrown out of engagement with their holding-pawls by pressing upon the button 11, connected with the post, extending through the under 65 part of the case, and the retracting-springs of said wheels will then return them to their starting-place.

I claim as my invention—

1. In a register and in combination, a shaft, as *a*, carrying a pointer, a ratchet-wheel fixed thereon, push and holding pawls, and a retracting-spring for said ratchet-wheel, a second ratchet-wheel fixed to a sleeve on the shaft, the same being provided with a pointer, and means for raising the wheels out of connection with their holding-pawls and retracting-springs, all substantially as described. 75

2. In combination with the shell or case having an incline formed on the bottom thereof, the shaft *a*, carrying the wheel *B*, the spring-arm, pawl, and retracting-spring for the same, said wheel having a lug projecting beyond its periphery, whereby in the rotation of the shaft the lug will ride up upon the incline on the bottom of the case, thus forcing the wheel 85 out of engagement with the pawl and allowing it to be returned to its normal position, substantially as described.

3. In combination, an indicator for registering the number of balls, connected to the shaft, a ratchet-wheel carried on said shaft, a pawl for holding the same, a push-pawl for operating it, a spring for retracting it, an incline formed on the bottom of the case, and a projection on the ratchet-wheel for coming in contact with said incline to elevate the ratchet-wheel and thereby release it from its holding-pawl, a sleeve mounted on the shaft, an indicator for registering the number of strikes connected therewith, a ratchet-wheel also attached thereto, a holding-pawl for said wheel and a push-pawl for operating it, a retracting-spring, an incline formed on the case, and a projection on said wheel adapted to engage with said incline to free said wheel from its holding-pawl, and an indicator to register the number of whole and half innings connected with a suitable ratchet-wheel, a holding-pawl for said wheel, and an operating-pawl for the same, substantially as described. 100 110

4. In combination with a suitable shell or case having inclines formed on the bottom thereof, the wheels *B* and *E*, the lugs carried thereon, adapted to ride up upon the inclines, the springs for returning the wheels to their normal position, and the spring for forcing them down for a continuation of the operation, substantially as described. 115

5. In combination with a suitable shell or case, the wheels *B* and *E*, carried on suitable shafts, holding-pawls for said wheels, a button for forcing up the shafts and thus elevating the wheels out of engagement with their pawls, springs for returning the wheels to their normal positions, and the spring for forcing them down for a continuation of the operation, substantially as described. 120 125

In testimony whereof I have signed my name to this specification in the presence of two subscribing witnesses.

JOHN A. YARGER.
